(57) **CLAIM**

The ornamental design for an exciter cap, as shown and described.

DESCRIPTION

FIG. 1 is a top perspective view of an exciter cap showing my new design;

FIG. 2 is a bottom perspective view thereof;

FIG. 3 is a front elevation view thereof; the rear elevation being a mirror image;

FIG. 4 is a top plan view thereof;

FIG. 5 is a side elevation view thereof, the opposite side being a mirror image;

FIG. 6 is a bottom plan view thereof; and,

FIG. 7 is a perspective view thereof, shown in environmental use.

The broken lines in the drawings represent unclaimed environmental subject matter and form no part of the claim.
